UNITED STATES PATENT OFFICE.

JACOB A. LIPSHITZ, OF BERLIN, GERMANY.

WATER HEATER.

Application filed February 9, 1924. Serial No. 691,714.

To all whom it may concern:

Be it known that I, JACOB A. LIPSHITZ, citizen of Russia, and resident of 37 Hauptstrasse, Gartenhouse, Shoenenberg, Berlin, 5 in the State of Germany, have invented certain new and useful Improvements in Water Heaters, of which the following is a specification.

My invention relates to apparatus for 10 heating water and has a particular reference to heaters in which the water comes in a direct contact with hot products of combustion.

The object of my invention is to provide 15 a heater in which water could be heated instantly to a desired temperature, in which the volume of water delivered and its temperature could be controlled independently, and in which the heat of products of 20 combustion could be utilized with the highest efficiency.

For this purpose I provide a jacketed chimney over a burner, forcing the hot gases 25 to flow downwards in the jacket and introducing water in the form of a spray in the path of these gases so that the water becomes instantly heated and, after condensation, can be used in any manner desired.

My invention is more fully described in 30 the accompanying drawings and specification in which—

Fig. 1 is a sectional elevation of my 35 heater, Fig. 2 is a detailed view of a centrifugal spraying nozzle, Fig. 3 is a top view partly in section, Fig. 4 is a sectional elevation of a simplified heater, Fig. 5 is a top view of same partly in section, and Fig. 40 6 is a partial sectional elevation of a modified construction.

My heater consists of a cylindrical conical chimney forming a combustion chamber 1 with a burner 2 underneath. This burner is made in the form of a hollow ring with a number of apertures 3 and a leading in supply pipe 4. The gas escaping from the 45 apertures 3 is ignited and burns in the form of jets of flame 5. These apertures may be on the side or on the top of the ring, and the burner itself may be made in any convenient shape and form for a gaseous or liquid fuel and, even, as a grate for a solid fuel (the latter variation not shown).

The chimney 1 with the burner 2 rest on 50 supporting legs 6 (the lower portion of which are not shown). A housing of jacket

7 is placed around the chimney 1, so that an annular chamber 8 is formed between the jacket and the chimney. A circular water well 9 is placed on top of the jacket or 60 housing 7 forming a top cover for this housing. The walls of the housing 7 are higher than the walls of the chimney 1 so that a space is provided for the gases to flow from the chimney into the chamber 8 (arrows 10). The well 9 has a central aperture 11 for a water feed pipe 12. The end of the pipe 12 is threaded for a nut 13, the well 9 being thereby clamped between this nut 13 and a flange 14 on the pipe 12. 65 Elastic gaskets 15 are placed between the nut 13 and the well and between the flange 14 and the well in order to prevent water leakage through these joints. A stiffening bushing 16 may be placed inside of the well 70 9 in order to prevent it from collapsing under the tension of the nut 11. Apertures 17 in the pipe 12 and 18 in the bushing 16 establish communication between the pipe 12 and the well 9. 75

The bottom of the well 9 is provided with a number of threaded apertures for spray nozzles 19 shown in detail in Fig. 2. A plug 20 is placed inside of each nozzle, a spiral separator 21 being wedged between the plug and the walls of the nozzle. The water, flowing downwards through the nozzle, follows a spiral path in the separator and thereby acquires a rapid rotation, so that the centrifugal force throws the water in the 80 form of a fine spray after it leaves the lower aperture 22 in the nozzle. I do not wish, however, to confine myself to this particular form of a nozzle, as any nozzle which 85 can give a fine spray of water may be used in my apparatus. 90

In order to control the flow of water through these nozzles a valve 23 is employed on a water feed pipe 24. The stem of this 95 valve ends with a tapered plug 25 adapted to close the bottom end of the pipe 12. 100

A second water feed pipe 26 extends from the valve 23 to the flange 14 under the well 9, encircling the first pipe 12. The upper 105 end of the pipe is closed with the flange 14 but is provided with spray pipes 27 terminating with nozzles 28. A flange 29 on the valve stem 30 serves as a closing valve for the lower end of the pipe 26. The taper of 110 the plug 25 is so proportioned that the pipe 12 is still closed when the pipe 26 is already

slightly opened, and only with further turning of the valve stem 30 both pipes become fully opened. With this arrangement it is possible to open at first only pipe 26 thereby 5 having a reduced amount of water flowing from the nozzles 28 only.

A vent hole 31 is provided at the bottom of the chamber 8 through which gases can flow into a condensing chamber 32 and a 10 chimney 33. A plurality of baffling plates 34 are placed in the condenser 32 at different angles with each other and so arranged that a stream of water flowing on these 15 plates from the well 9 through a nozzle 34', is broken into a plurality of sprays in opposition to the gaseous products of combustion flowing from the mixing chamber 8 into the chimney 33.

The water from the nozzles and from the 20 condenser collects at the bottom of the mixing chamber 8 and is removed through a faucet 35.

In order to use my heater for a shower bath I provide a second valve 36 with a 25 nozzle 37 in a chamber 38 formed in the faucet 35. A Venturi tube 39 is placed above the nozzle 37 leading through a vertical pipe 40 to a shower attachment 41.

The operation of my heater is as follows.

30 The fuel is turned on and ignited in the burner, then the valve handle 30 turned off to let the water flow through the pipe 12 into well 9 and nozzles 19, and through the 35 pipe 26 into pipes 27 and nozzles 28. The water will emerge from these nozzles in the form of a fine spray, collecting at the bottom 40 of the chamber 8. The hot gases from the chimney 1, flowing in the same direction as this spray of water, will heat the water particles, exhausting with most of its heat 45 taken away into the condenser 32. Here the last of the heat of the gases will be taken away from them by the opposite stream of water from the baffling plates 34. This 50 stream or spray of water will also condense whatever steam may have been generated in the mixing chamber 8, the condensate flowing back into this chamber. The heated water from the bottom of the mixing chamber flows into a well 38 and delivery pipe 35.

If the valve stem 30 is turned further then the cone 25 leaves an opening in the lower end of the pipe 12 thereby admitting water 55 into this pipe and through apertures 16 and 18 into the well 9 and nozzles 19. A larger volume of water will be then admitted into the mixing chamber 8 through combined action of the nozzles 28 and 19.

60 Water being delivered to the pipes 12 and 26 under a certain pressure, it forces the spray from the nozzles into the chamber 8 with a considerable velocity filling completely the circular space in this chamber with a water mist which acts like a piston, 65 thereby creating a strong suction effect on

the gases from the combustion chamber 1. This artificial draft helps materially to obtain a perfect combustion at the burners without any assistance from the chimney 33. With this arrangement it is possible to extract all the available heat from the gaseous products of combustion before they reach the chimney 33 as my heater does not depend on the chimney draft for its proper 70 operation. 75

With a double row of nozzles 19 and 28 and a double valve 23 it is possible to regulate very finely the amount of water delivered and its temperature. With a reduced amount of water needed and a throttled valve fewer nozzles are set in operation, so that the water leaves these nozzles with a sufficient force to break itself into a fine spray which is essential for the proper functioning of my apparatus. If 80 there was only one set of nozzles, then with the valve throttled below a certain limit the water would not have sufficient velocity to form a spray and would leave the nozzles in drops. The suction effect will then be lost 85 and the efficiency of the apparatus impaired. 90

In order to operate the shower attachment the valve 36 is opened thereby admitting water from the water supply pipe 24 into the nozzle 37. The water, emerging 95 at high speed, passes into the Venturi tube 39 forcing also some of the hot water from the well 38 into the shower pipe 40 and the shower nozzle 41. The force and the temperature of the shower may be regulated by 100 turning the valve handle 42.

A simplified construction is illustrated in Figs. 4 and 5. Here only one set of spray nozzles 19 is used, consequently a single 105 acting valve 23 is sufficient. Condenser with baffling plates is also eliminated. This construction may be used when a cheaper device is required, and when wide regulation of the water delivered is not 110 needed. 115

Another modification is represented in Fig. 6 with an open upper well 43 under a common roof 44 with the condenser 32. The water from the pipe 12 is delivered through nozzles 45 into the well 43, and from the pipe 26 into spray nozzles 28. The remainder of the construction (not shown) is the same as in Fig. 1. 120

Important advantages of my water heater are that it is very efficient on account of the full utilization of the heat of the burned fuel, also because it is adapted to produce an artificial draft which causes better and more complete combustion, that the heated water is delivered very quickly after the apparatus has been set in operation, and that the temperature of this water and its amount can be efficiently regulated. 125

I claim as my invention:

1. In a water heater, the combination with

5 a burner, a combustion chamber containing said burner, a mixing chamber adjacent to said combustion chamber, and adapted to receive the products of combustion from said combustion chamber, means to introduce water in the form of a fine spray into said mixing chamber in the same direction in which said products of combustion are flowing, and means to remove the heated 10 water from the bottom of said mixing chamber.

15 2. In a water heater, the combination with a burner, a combustion chamber enclosing said burner, a mixing chamber adapted to receive products of combustion from said combustion chamber, means to introduce water in the upper portion of said mixing chamber, said means being adapted to distribute water in the form of a fine spray and 20 to direct said spray so as to increase the draft through said burner.

25 3. In a water heater, the combination with a burner, a combustion chamber extending vertically above said burner, a mixing chamber encircling said combustion chamber, a chimney connected with the lower portion of said mixing chamber, a water well above said combustion and said mixing chamber, a plurality of nozzles in said mixing chamber 30 connected with said well and adapted to deliver water from said well in the form of a fine spray and further adapted to force said spray in a direction of movement of the products of combustion from said 35 burners.

40 4. In a water heater, the combination with a burner, a combustion chamber above said burner, a mixing chamber extending downwards from the upper end of said combustion chamber, a water well above said mixing chamber, an exhaust chimney connected with the lower portion of said mixing chamber, a plurality of nozzles in said water well directed into said mixing chamber, means to impart a rotary movement to the water passing through said nozzles, and means to remove the water condensed at the 45 bottom of said mixing chamber.

50 5. In a water heater, the combination with a burner, a combustion chimney above said burner, a mixing chamber arranged concentrically with said combustion chimney, the upper portion of said combustion chimney and of said mixing chamber being in a communication with each other, an exhaust chimney connected with the lower portion of said mixing chamber, means to deliver water into the upper portion of said mixing chamber, including a plurality of nozzles in 55 a cooperative relation to said water delivering means, spiral cores inside of said nozzles, and means to regulate the amount of water delivered to said nozzles.

60 6. In a water heater, the combination with a burner, a cylindrical combustion chamber

inclosing said burner, a mixing chamber adapted to receive products of combustion from said combustion chamber, means to deliver water in the form of a fine spray into said mixing chamber, an exhaust chimney 70 connected with said mixing chamber, and means to condense the water vapors reaching said chimney from said mixing chamber.

75 7. In a water heater, the combination with a burner, a combustion chamber enclosing said burner, a mixing chamber connected with said combustion chamber, means to introduce water in the form of a fine spray in said mixing chamber in the path of the products of combustion from said combustion chamber, means to regulate the amount of water delivered into said mixing chamber, and means to maintain said fine spray in said mixing chamber with a reduced amount of water delivered.

80 8. In a water heater, the combination with a burner, a combustion chamber enclosing said burner, a mixing chamber connected with said combustion chamber, a water well on top of said chambers, a plurality of nozzles in said well directed into said mixing chamber, a pipe passing through said combustion chamber and adapted to deliver cold water to said well, means to clamp said well to said pipe, and means to regulate the water 85 flow through said pipe.

90 9. In a water heater, the combination with a burner, a combustion chamber enclosing said burner, a mixing chamber connected with said combustion chamber, a plurality of nozzles in the upper portion of said mixing chamber, means to deliver cold water to said nozzles, means to regulate the amount of water delivered to said nozzles, and means to regulate the number of nozzles in operation in accordance with the amount of water delivered.

100 10. In a water heater, the combination with a burner, a combustion chamber enclosing said burner, a mixing chamber encircling said combustion chamber, a water well on top of said chambers, a plurality of nozzles in said well directed into said mixing chamber, a second water supply pipe leading into said mixing chamber, a plurality of nozzles connected with said second water supply pipe, a common valve for said water supply pipes, said valve being adapted to open one of said pipes ahead of the other, and means to deliver cold water to said valve.

110 11. In a water heater, the combination with a burner, a combustion chamber enclosing said burner, a mixing chamber concentric with said combustion chamber, a water well on top of said chambers, a plurality of nozzles in said water well, a pipe connected with said well and passing through said combustion chamber, a second pipe encircling said first pipe and leading to the top of said mixing chamber, a plurality of 120 125 130 nozzles in said second pipe.

nozzles connected with said second pipe in said mixing chamber, a valve adapted to receive both of said pipes, a flat disc in said valve adapted to close the outer pipe, a cone 5 in said valve adapted to close the inner pipe, said disc being adapted to open the outer pipe before said cone opens said inner pipe, and means to deliver water to said valve.

12. In a water heater, the combination 10 with a burner, a plurality of chambers adapted to conduct the products of combustion from said burners, means to produce a moving column of a fine water mist in said chambers, the movement of said water mist 15 being in the same direction in which said products of combustion are moving, and means to remove the condensed and heated water from said chambers.

13. In a water heater, the combination 20 with a burner, a plurality of chambers adapted to conduct the products of combus-

tion from said burners, a plurality of nozzles in the path of said products of combustion, means to impart a rotary motion to the water passing through said nozzles, means to deliver water to said nozzles, and means to remove the condensed and heated water from 25 said chambers.

14. In a water heater, the combination 30 with a burner, a plurality of chambers adapted to conduct the products of combustion from said burner, means to introduce water in the form of a fine spray in the path of said products of combustion, a condenser adapted to condense the water vapors from 35 said chambers and means to remove the condensed and heated water from said chambers.

Signed at Berlin in the country of Germany and State of Prussia, this 23rd day of January A. D. 1924.

JACOB A. LIPSHITZ.
